US0D1015706S

(12) **United States Design Patent** (10) **Patent No.:** **US D1,015,706 S**
(45) **Date of Patent:** **** Feb. 27, 2024**

(54) **FOOTWEAR**

(71) Applicant: **Target Brands, Inc.**, Minneapolis, MN (US)

(72) Inventor: **Austyn Dunham**, Minneapolis, MN (US)

(73) Assignee: **Target Brands, Inc.**, Minneapolis, MN (US)

(**) Term: **15 Years**

(21) Appl. No.: **29/754,385**

(22) Filed: **Oct. 9, 2020**

(51) **LOC (14) Cl.** 02-04

(52) **U.S. Cl.**

USPC **D2/959**; D2/947; D2/951; D2/957

CLAIM

The ornamental design for a footwear, as shown and described.

DESCRIPTION

FIG. 1 is a front, top and right side perspective view of an embodiment of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a back, bottom, and left side perspective view thereof.

The broken lines in the drawings show portions that form no part of the claimed design.

1 Claim, 6 Drawing Sheets
